SPRING SASH BALANCE

Aloysius F. Mantz, Los Angeles, Calif.

Application April 1, 1936, Serial No. 72,066

6 Claims. (Cl. 16—198)

My invention relates to a spring sash balance, and the construction herein described is an improvement on the spring sash balance covered by the United States Letters Patent No. 1,669,990, issued to me May 15, 1928, also Patent No. 1,898,584, issued to me February 21, 1933.

The principal objects of my present invention are to generally improve upon and simplify the construction of the sash balance covered by my aforesaid patents, and particularly, Patent No. 1,669,990, as well as other forms of similar spring sash balances, and further, to provide a sash balance that is relatively simple in construction, inexpensive of manufacture, capable of being readily installed and which is practically automatic in operation and functions.

Further objects of my invention are to provide a spring sash balance having two wire or cable-receiving drums mounted on a common axle, with a spiral spring arranged between said axle and one of the drums, and means arranged between the axle and the other drum for transmitting the resistance offered by the spiral spring to said other drum, in other words, utilizing the yielding resistance offered by one coil spring for two independently operating wire or cable carrying drums.

Further objects of my invention are to provide a spring sash balance that is entirely automatic in action, capable of being readily adjusted so as to regulate the tension of the spring in relation to the weights of the window sash with which the balance is associated, and further to provide a balance that is noiseless in operation, of strong and durable structure and very effective in service.

With the foregoing and other objects in view, my invention consists in certain novel features of construction and arrangements of parts that will be hereinafter more fully described and claimed and illustrated in the accompanying drawing in which:

Fig. 1 is a front elevational view of a spring sash balance constructed in accordance with my invention.

Fig. 2 is a side elevational view looking in the direction indicated by the arrow 2 in Fig. 1, with the upper portion of the housing broken away and in section.

Fig. 3 is a side elevational view of the spring sash balance looking in the direction indicated by the arrow 3 in Fig. 1, with the upper portion of the housing broken away and in section.

Fig. 4 is an enlarged vertical section taken on the line 4—4 of Fig. 1.

Fig. 5 is a cross-section taken on the line 5—5 of Fig. 4.

Fig. 6 is a cross-section taken on the line 6—6 of Fig. 4.

Fig. 7 is an elevational view of a sash balance unit that includes two of the single units, and which construction may be employed in connection with a relatively heavy window sash.

Fig. 8 is a perspective view of a bow spring that is utilized in my improved sash balance.

Fig. 9 is a perspective view of the axle on which the drums are mounted, and to which the inner end of the spiral spring is connected.

Fig. 10 is a detail vertical section of the combined hook and glider that is utilized for attaching the wires or cables to the window sash.

Referring by numerals to the accompanying drawing, and particularly to the construction illustrated in Figs. 1 to 6 inclusive, which illustrate a preferred embodiment of my invention, 20 10 designates the front plate of the housing, which plate is provided in its end portion with apertures 11 for the reception of screws that rigidly secure the sash balance to the stiles of the window frame.

Formed at or near the center of plate 10 is a circular aperture 12, and formed around said aperture and projecting rearwardly therefrom, is a short circular flange 13.

To combine with plate 10 in providing a housing for the operating parts of the balance, a substantially rectangular plate 14 is applied to the rear face of plate 10, and formed integral with said plate 14 is a circular cup-shaped housing 15 having a wall 16 that occupies a plane parallel with plate 10.

Plate 14 and housing 15 are detachably connected to plate 10 by means of ears 16a that project from the side edges of plate 10, and which are bent around the adjacent edges of plate 14, 40 and to further secure these parts, ears or lips 17 project from the upper and lower portions of cup 15, and said ears or lips pass through slots 18 that are formed in plate 10 and then bend downwardly against the face of said plate 10.

Projecting inwardly from the center of the wall 16 of cup 15 is a circular stud 19 that functions as a bearing for a tubular axle 26, the opposite end of which has bearing on flange 13. This tubular axle is provided with a narrow longitudinally disposed slot 27, and formed in the end of said tubular shaft that engages the flange 13 are short longitudinally disposed notches 28.

Positioned within the rear portion of the housing formed by the cup 15 and front plate 10, is

a drum comprising a disc 29 with the edge of which is formed integral a circumferential channel-shaped flange 30. Disc 29 is provided with a centrally arranged aperture 31 for the reception 5 of the axle 26, thereby enabling the drum comprising the disc 29 and flange 30 to rotate freely on the axle, and arranged within said drum, is a spiral spring 32, the inner end of which terminates in a hook 33 that engages in slot 27 in the 10 axle, and the outer end of this spiral spring is secured in any suitable manner to flange 30.

Secured to and adapted to wind on flange 30 is a wire or cable 34 which passes downwardly from one side of the drum through an aperture 35 that 15 is formed in the circular wall of the drum, thence forwardly and downwardly through coinciding apertures 36 that are formed through the lower portions of plates 10 and 14.

The lower end of this wire or cable carries a 20 hook, or other suitable means, whereby it may be detachably connected to one of the sashes of the window.

Occupying the space within the housing between the drum comprising disc 29 and flange 30, 25 is a drum comprising a disc 37 with the edge of which is formed integral a circumferential flange 38 that is channel shaped in cross-section. This drum is mounted to rotate freely upon the tubular axle 26. A wire or cable 39 is secured to and 30 adapted to wind on the flange 38, and said wire or cable extends downwardly from one side of said drum through an aperture 40 that is formed through the circular wall 15 of the housing on the opposite side from aperture 35, and said cable 35 extends from said aperture 40 downwardly through coinciding apertures 41 that are formed through the lower portions of plates 10 and 14.

Aperture 41 is located on the opposite side of the housing from aperture 36, through which 40 passes cable 34, and the lower end of said wire or cable 39 carries a hook 42, or other means, whereby it may be detachably secured to one of the window sashes. Formed through plate 10, preferably above the central aperture 12, is a small 45 aperture 43, and formed through the disc 37 of the drum that is positioned immediately behind front plate 10, is a series of apertures 44 arranged in a circle so that they will coincide with aperture 43, as the drum is rotated. These apertures 50 are provided in order that a nail, or the like, may be inserted through aperture 43, and through one of the apertures 44, that hold the drum in which said apertures are formed against rotation when the tubular shaft 26 is rotated to wind or 55 unwind spring 32, and thereby increase or decrease the tension thereof.

A ratchet wheel comprising a disc 45 provided with radially disposed teeth 46 is provided with arcuate slots 47, for the reception of those portions of the tubular shaft 26 between the notches 28, thus mounting said ratchet wheel upon the tubular shaft so as to rotate therewith.

Formed in the center of disc 45 is a slot or non-circular opening 48 adapted to receive the point 60 of a screw driver, or like tool, that is utilized in rotating the tubular shaft.

Pressed rearwardly from disc 37 is a circular 65 row of lugs or teeth 49 that are provided at their forward ends with straight faces or shoulders, 70 that are adapted to be engaged by the teeth 46 of the ratchet wheel, and these lugs or teeth 49 are shaped so that when the ratchet wheel is rotated in one direction so as to wind spring 36, the teeth 46 of said ratchet wheel will slide freely over 75 said lugs or teeth 49.

A bow spring 50 is provided in its center with a non-circular opening 51 for the reception of those portions of the tubular axle 26 between the notches 28, and when properly positioned on said axle, the central portion of said bow spring bears 5 against the disc 45 of the ratchet wheel, and the ends of said spring bear against the disc 29 of the drum that incloses spiral spring 32. (See Fig. 4.)

When my improved sash balance is installed, plate 10 is secured to the window stile by means 10 of screws that pass through the apertures 11, and housing 15 occupies an opening that is formed in the stile. The hooks 42 or other fastening means carried by the ends of the wires or cables 34 and 39 are connected to the lower portions 15 of the upright side members of the window sash.

The spring tension required to counter-balance the weight of the window sash is obtained by inserting the point of a screw driver, or the like, 20 in slot 48, and rotating tubular shaft 26, so as to wind said spring to the desired degree, and during this operation, the drum comprising disc 37 and channel 38 is held against rotary movement by the insertion of a nail, or the like, through 25 aperture 43 and through one of the apertures 44. During this tensioning operation, the teeth of the ratchet wheel ride past the teeth or lugs 49 on disc 37, and which movement of the ratchet wheel is permitted by bow spring 50, which flexes slightly 30 as the teeth of the ratchet wheel pass the teeth 49.

When the sash balance is properly installed and the spring 32 is adjusted as just described, and both sash are closed, the spring is partially wound so that a certain degree of tension prevails 35 in said spring.

When the lower sash is raised the wire or cable that is connected thereto is wound upon its drum, due to the unwinding of the spring 32, 40 which is under tension and as the lower sash is closed the cable connected thereto will rotate the drum to which it is connected so as to rewind the spring. When the upper sash is lowered the wire or cable connected thereto will rotate the drum to which it is connected so as to wind up 45 the spring and when the upper sash is closed the spring under tension will act to rotate the corresponding drum to wind thereon to the cable that is connected to said upper sash.

When the drum comprising disc 29 and flange 50 30 is rotated anti-clockwise, the spring 32 is wound from the outside, due to the fact that the outer end of said spring is connected to flange 30, and when the drum comprising disc 37 and flange 38 is rotated clockwise, the spring is 55 wound from the inside, due to the fact that the ratchet wheel that is rotated as a result of the engagement of the lugs or teeth 49 with the teeth of said ratchet wheel imparts rotary movement to the latter, and as said ratchet wheel is 60 mounted on the end of the tubular shaft 26, the latter is rotated. The inner end of spring 32 is connected to the tubular axle 26, so that under such conditions, the spring is wound from the inside.

Under normal operating conditions, spring 32 which is partially wound, is poised in equilibrium, and functions as a counter-balance for both the upper and lower sash. The tension of the spring under normal conditions is insufficient to move 70 either one of the sash, due to the weight thereof, plus the frictional resistance resulting from the engagement of the stiles of the sash with the window frame, the parting strips and the stops. Further, a certain degree of resistance is 75

developed by the engagement of the wires or cables 34 and 39 with the edges of the openings 35 and 40, and likewise the edges of the openings 36 and 41, through which said wires or cables pass.

The ratchet wheel 45 that is mounted on the end of the tubular axle 26 so as to rotate therewith, provides a driving connection between the inner end of the spring 32 and the drum comprising the disc 37 and flange 38, inasmuch as the teeth of said ratchet wheel normally engage the teeth 49 on said drum, but at the same time, the connection is such that the tubular axle may be rotated to impart the proper degree of tension to the spring 32.

In Fig. 7 I have illustrated a two unit structure particularly designed for use in connection with the relatively heavy sash. In this construction, an elongated housing 55 in which is mounted for rotation, one above the other, two of the tubular shafts 26, and each shaft having mounted thereon, two cable or wire-carrying drums. The cables or wires 56 from these drums, pass through openings 57 in the lower portion of the front wall of the housing, and connected to the lower ends of each pair of wires is a sash engaging hook such as 42. Thus in the one structure, each shaft is counter-balanced by two springs.

In Fig. 10, I have shown in vertical section, one of the hooks utilized for connecting the ends of the wires or cables to the sash, and such hook comprises a substantially L-shaped body portion 42a and with a prong or prongs 42b projecting upwardly from the horizontal arm of said body portion, and which prongs are driven into the lower rail of the window sash. Depending from the vertical leg of the body of the hook is a curved plate 42c, which frictionally engages the face of the stile of the window frame, and thus the hook performs the functions of both an attaching hook for the wire or cable, and a glider for the sash in its vertical movement.

The wire or cable that connects the sash with the balance passes through an aperture 42d formed in the upper portions of the parts 42a and 42c, and the lower end of said wire or cable passes through an aperture 42e that is formed in the horizontal leg of the hook.

In my improved sash balance, the spring 32 functions as a resilient and yielding equalizer between the wire or cable connections and the two sash of the window, and that said spring yieldingly supports and balances the two sash in both open and closed positions, and at any and all intermediate points in their travel.

The spring pressed ratchet 45 engaging the detents 49 on one drum functions as a connection between the inner end of the spiral spring that is secured to tubular shaft 26, and the drum with which the ratchet wheel engages, and the engagement of said ratchet wheel with the drum is such that the latter may be held stationary while the tubular shaft carrying the ratchet is rotated to wind the spiral spring so as to produce therein, the required degree of tension.

Thus it will be seen that I have provided a spring sash balance that is relatively simple in construction, practical and noiseless in operation, inexpensive of manufacture, capable of being readily installed and very effective in performing the functions for which it is intended.

It will be understood that minor changes in the size, form and construction of the various parts of my improved spring sash balance may be made and substituted for those herein shown and described without departing from the spirit of my invention, the scope of which is set forth in the appended claims.

I claim as my invention:

1. In a spring sash balance, a pair of cable-carrying drums mounted for independent rotary movement, a spiral spring having its outer end connected to one of said drums and means adjustably connecting the inner end of said spring with the other drum.

2. In a spring sash balance, a rotatably mounted shaft, a pair of cable-carrying drums mounted for independent rotation upon said shaft, a spiral spring having its outer end connected to one of said drums, and its inner end connected to said shaft and means adjustably connecting said shaft and the other one of said drums.

3. In a spring sash balance, a rotatably mounted shaft, a pair of cable-carrying drums mounted for independent rotation upon said shaft, a spiral spring having its outer end connected to one of said drums, and its inner end connected to said shaft, detents formed on the other one of said drums and a ratchet wheel carried by said shaft, with the teeth of said ratchet wheel in engagement with said detents.

4. In a spring sash balance, a housing, a shaft journaled therein, a pair of drums mounted for independent rotary movement on said shaft, a flexible member secured to and carried by the periphery of each drum, a spiral spring having its outer end secured to one of said drums, and its inner end secured to said shaft and a releasable driving connection between said shaft and the other one of said drums.

5. In a spring sash balance, a pair of cable-carrying drums mounted for independent rotary movement, a spiral spring having its outer end connected to one of said drums, means adjustably connecting the inner end of said spring with the other drum and means for holding the second mentioned drum against rotation while winding movement is imparted to said spiral spring.

6. A spring sash balance adapted to be positioned in an opening in a window jamb, which balance includes a pair of cable-carrying drums and a spiral spring, the outer end of which spring is connected to one of said drums, and the inner end being adjustably connected to the other one of said drums, and which drums when positioned in the opening in the jamb, occupy positions substantially at right angles to the plane occupied by the sash that bear against said jamb.
